UNITED STATES PATENT OFFICE.

DON L. GALUSHA, OF WINCHESTER, MASSACHUSETTS.

FUEL-SUPPLY SYSTEM.

1,256,785.

Specification of Letters Patent. Patented Feb. 19, 1918.

Application filed May 17, 1917. Serial No. 169,220.

To all whom it may concern:

Be it known that I, DON L. GALUSHA, a citizen of the United States, residing at Winchester, in the county of Middlesex and 5 State of Massachusetts, have invented an Improvement in Fuel-Supply Systems, of which the following is a specification.

My invention relates to a fuel supply system for automobiles, and has especial 10 reference to the vacuum feed system, although it may relate equally well to the pressure feed system.

The object of my invention is in the provision of a fuel supply system having means 15 for a main and reserve supply of fuel, and in which the exhaustion of the main fuel supply causes the operation of a suitable alarm, and in which the exhaustion of the main fuel supply may permit the operation 20 of the engine upon the reserve fuel supply and the simultaneous operation of a suitable alarm.

The means by which I carry out the object of my invention is in the provision of 25 a dual set of fuel feed pipes extending from the vacuum tank to the fuel supply tank, one of which pipes extends into said tank a greater distance than the other, and the distance between the ends of the two pipes 30 constitutes a measure of the reserve fuel supply. Suitable mechanism is associated with the dual feed pipes, whereby the cessation of fuel flow in one of said pipes will cause the automatic operation of a suitable 35 alarm and admit of either manual or automatic control of the reserve fuel supply.

Figure 1 is a diagrammatic representation of my invention.

Fig. 2 is a modification of Fig. 1.

40 Fig. 3 is a further modification of Fig. 2. Fig. 4 is a fragmentary sectional detail of Fig. 3.

Fig. 5 is a further modification of Fig. 2.

Fig. 6 is a further modification of Fig. 2.

45 Fig. 7 is an enlarged sectional view of the indicator of Fig. 6.

Fig. 8 is a modification of Fig. 7.

Fig. 9 is a modification of Fig. 6.

50 Fig. 10 is an enlarged sectional detail of the float valve of Fig. 9.

As here shown, my invention is applied to an automobile using a well-known vacuum fuel feed system, although it may equally well be applied to other vacuum 55 fuel feed systems or to a pressure feed system, in which the vacuum tank comprises the outer shell 10, which constitutes the

emptying chamber, and the inner shell 11, which constitutes the filling chamber. The filling chamber contains a float 12 and valve 60 mechanism which is adapted to be automatically operated by said float to connect said filling chamber alternately with the engine manifold, through suction pipe 13, and to the atmosphere through atmospheric 65 pipe 13' and outer chamber 10 is provided with a fuel pipe 15 leading to the carburetor of the engine, and is in permanent communication with the atmosphere through said pipe 13' which opens into the top of 70 said outer chamber, all of which is usual with the vacuum system chosen to illustrate the application of my invention.

The main fuel feed pipe 14 extends from the vacuum tank to the fuel supply tank 16, 75 which is usually disposed at the rear of the automobile, and terminates therein at a short distance above the bottom thereof.

An auxiliary feed pipe 17 joins the main feed pipe at some point near the vacuum 80 tank and extends into the fuel supply tank and terminates therein at some distance above the end of the main fuel pipe. The distance between the ends of the two pipes is a measure of the reserve fuel supply. 85 Supply tank 16 is in permanent communication with the atmosphere.

A valve 18 is placed in the auxiliary fuel pipe at some convenient point, and a universal joint 19 and rod 20 connect its stem 90 with a handle or lever 21 arranged on the dash or cowl 22 of the automobile.

In the normal operation of the apparatus, with valve 18 open and supply tank 16 filled with fuel, the vacuum created in the filling 95 chamber of the vacuum tank by the suction of the engine acting through the suction pipe 13, causes a flow of fuel in both the main and the auxiliary fuel pipes from the supply tank 16 to the vacuum tank. Fuel 100 will continue to flow in both pipes 14 and 17 until the fuel level in the supply tank 16 reaches the level $a-a$ just below the open end of the auxiliary fuel pipe 17. When this level is reached, air is drawn in said 105 pipe and the vacuum at the junction of the dual fuel pipes 14 and 17 is broken, and consequently the fuel in pipe 14 returns to the supply tank and only air is drawn into the vacuum tank. The engine now 110 operates on the fuel contained in the vacuum tank, and, as soon as this is exhausted, the engine stops, thus giving warning to the operator of the exhaustion of the main fuel

supply. The operator then moves lever 21 on the dash of the automobile to a position coinciding with the closed position of valve 18 in the auxiliary pipe line, and spins the 5 engine with closed throttle. Since the auxiliary fuel pipe 17 is now closed, the suction produced by this operation draws fuel through pipe 14 to fill the vacuum tank, and the engine again operates on fuel which is 10 now supplied by one pipe only. The engine may now run until the reserve supply is exhausted.

The positions of lever 21 on the cowl, corresponding to the open and closed positions 15 of valve 18, may be suitably marked to indicate the operation of the engine on the main or the reserve fuel supply.

In the apparatus above described, the only 20 warning given of the exhaustion of the main fuel supply is the stopping of the engine, and the reserve fuel supply is manually controlled.

Fig. 2 represents a modification of my invention in which a visual signal of exhaustion 25 of the main fuel supply is provided upon the cowl of the automobile, and the necessity of manual reserve fuel supply control is obviated.

The main fuel pipe 14 is connected, as in 30 Fig. 1, directly to the vacuum tank, but an auxiliary float chamber 23 is interposed in the auxiliary pipe 17 at some point adjacent the vacuum tank, and the inlet to the float chamber is controlled by a valve 24 controlled by the float 25. When supply tank 35 16 has a fuel supply extending above the opening of auxiliary pipe 17, chamber 23 is full of fuel and valve 24 is consequently open, but when the main fuel supply is exhausted, chamber 23 is exhausted of fuel and valve 24 is closed, thus preventing access of air into chamber 23 and the consequent breaking of the vacuum in the vacuum tank, as would otherwise occur.

45 A pipe 26 is connected into the main fuel pipe 14 near its junction with auxiliary pipe 17, and extends into the top of float chamber 23 and is provided with a flap valve 27 for a purpose hereafter to be explained.

50 A dash-indicating device is interposed in the auxiliary fuel pipe 17 at some convenient point, and comprises a glass tube 28 suitably supported in members 29. One of the members 29 is provided with a ball check valve 30, which, acting in conjunction with loop 31 in pipe 17 serves to prevent the draining of pipe 17 during the periods when atmospheric pressure exists in the vacuum tank.

A ball 32 of cork or other suitably buoy- 60 ant material is disposed within glass tube 28 and in the normal operation of the system, occupies the top part of the tube, being maintained therein by its buoyancy, and is, therefore, out of view. When, however, the 65 main fuel supply is exhausted, fuel is with-

drawn from the glass tube and the ball 32 sinks to the bottom of the tube and appears to view, thus providing a visible signal of the exhaustion of the main fuel supply.

In the normal operation of this modifica- 70 tion of my invention, with a supply of fuel in tank 16 in excess of the reserve supply, auxiliary float chamber 23 is filled with fuel, and fuel flows into the vacuum tank 10, due to the vacuum therein, through both fuel 75 pipes 14 and 17, and the ball 32 in the dash-indicator is invisible, thus indicating a sufficiency of fuel.

When, however, fuel in the main supply 80 tank 16 is exhausted to a point below the opening of auxiliary fuel pipe 17 in said tank, air is drawn through said pipe into said tank by the suction of the engine, and the pipe is exhausted of fuel and ball 32 appears to view, indicating the operation of the 85 engine on the reserve supply. Since chamber 23 is now at atmospheric pressure, an immediate flow of fuel will take place from said chamber into the main fuel tank 16 through main fuel pipe 14 until the level of 90 the fuel in said chamber has reached a point sufficient to permit the closing of valve 24 in pipe 17 by float 25. Fuel will then be drawn into the vacuum tank through pipe 14 alone by the suction of the engine until the reserve 95 supply is exhausted.

Pipe 26 with valve 27 is connected between the main fuel pipe 17 and chamber 23 to provide for the initial filling of said chamber with fuel. When the chamber 23 is empty 100 and valve 24 consequently closed and the engine is in operation, the suction produced thereby will cause fuel to flow in the main pipe 14 toward the vacuum tank; and, because of the opening of pipe 26 into pipe 14 105 and the fact that both ends of pipe 26 are at the same pressure, fuel will flow through pipe 26 and valve 27 into chamber 23 until float 25 is raised sufficiently to open valve 24, after which the engine suction will cause a 110 simultaneous flow of fuel through pipes 17 and 14 until the main fuel supply is exhausted.

Fig. 3 is a modification of Fig. 2, in that the auxiliary float chamber is dispensed 115 with, and the float 25' placed directly in the emptying chamber 10 of the vacuum tank. Float 25' is attached to a lever 33 pivoted at 34, which has its free end pivoted to a rod 35, which is movably connected to an arm 36 secured to shaft 37. Said shaft 37 is journaled in the outer and inner tanks 10 and 11 and projects therethrough. The end of said shaft terminating within the filling chamber 11 has secured to it an arm 38, 120 which extends on the opposite side of shaft 37 from arm 36 and controls a valve 39 in the auxiliary fuel pipe 17 which opens into the filling chamber. The other end of shaft 37 terminates in an arm 40 operably con- 130

nected to a rod 41 extending to a suitable indicating device 42.

- Assuming the main fuel tank to be filled with fuel, the vacuum tank empty, float 25' in its low position, and valve 39 in the auxiliary pipe 17 consequently closed, float valve 12 in the filling chamber 11 to be at its lowest point and consequently the atmospheric valve 43 to be closed and suction valve 44 (see Fig. 1) to be open, and the engine rotated, the suction caused by the rotation of the engine creates a vacuum in the filling chamber and fuel is drawn from the main supply tank 16 through pipe 14 into 10 said filling chamber and fills this chamber, valve 45 being meanwhile maintained upon its seat by atmospheric pressure. When a certain amount of fuel has entered the filling chamber, float 12 is raised and operates 20 to close the suction valve 44 and to open the atmospheric valve 43. Valve 45 now opens, due to the weight of fuel acting upon it, and permits fuel to flow from the filling chamber 11 into emptying chamber 10, raising float 25' and consequently opening valve 25 30 in the auxiliary fuel pipe 17. As the fuel level in the filling chamber descends, the float valve 12 is correspondingly lowered and operates to open suction valve 44 and close atmospheric valve 43. As valve 39 is maintained open by the position of float 25' in the emptying chamber 10, the suction of the engine acting through pipe 13 creates a flow of fuel through both the main fuel pipe 35 14 and the auxiliary pipe 17 until the filling chamber is filled with fuel to the predetermined level, when the atmospheric valve 43 will be opened and the suction valve 44 will be closed and fuel will flow into the emptying chamber 10 and maintain valve 39 in 40 auxiliary pipe 17 open.
- This alternate filling of the chamber 11 through both the main and auxiliary fuel pipes, and its consequent emptying into the emptying chamber 10, will continue until the main fuel supply is exhausted, and the fuel in supply tank 16 is below the opening of the auxiliary pipe 17. Upon the breaking of the seal over the end of pipe 17 because 45 of the exhaustion of the main fuel supply, filling chamber 11 will be maintained at atmospheric pressure, and the engine suction will be ineffective in causing a flow of fuel through the main pipe 14 and consequently 50 the fuel level in emptying chamber 10 will be lowered, and at some fuel level therein, the float 25' will be actuated to close valve 39 in the auxiliary pipe 17. As the filling chamber is now closed to the atmosphere, the 55 suction of the engine will cause fuel flow through the main pipe 14 into the filling chamber and subsequently into the emptying chamber 10, where it causes the float 25' to be raised and valve 39 again opened.
- 60 With the exhaustion of fuel from the empty-

ing chamber 10, the cycle of operation is again repeated, the engine drawing the reserve fuel through pipe 14 until the supply is exhausted.

Indicator 42 is maintained inoperative 70 while fuel is being drawn through both fuel pipes, because float 25' is maintained in its raised position, being always submerged in fuel, but, as soon as the main supply is exhausted and fuel is supplied through the 75 main pipe 14 only, the float 25' is alternately raised and lowered, and consequently operates the indicating device 42, and gives notice of the exhaustion of the main fuel supply. 80

A modification of the form of my invention illustrated by Fig. 2 is shown in Fig. 5, in which the auxiliary float chamber 23 is disposed adjacent the cowl of the automobile and the indicating-means are directly connected thereto. 85

As here shown, the dash-indicating device, which consists of a glass tube 28 secured in liquid-tight relation between two members 29, and which has disposed therein the indicating ball 32, is connected to auxiliary float tank 23 by two pipes 46 and 47 of which pipe 47 has an upward slope from the dash-indicator to the tank 23 to permit the escape of air that might otherwise become 95 trapped in the indicator.

The opening of the two pipes 46 and 47 is below the normal level of fuel in tank 23 and consequently the dash-indicator and connecting pipes are normally full of fuel, 100 and the ball 32 is maintained, by its buoyancy, in the upper part of the indicator, out of view. When, however, the main supply of fuel becomes exhausted, the tank 23 becomes emptied of fuel as has been heretofore 105 described, and consequently the ball 32 in the dash-indicator descends into view and gives a visible indication of an insufficient supply of fuel.

A further modification of my invention 110 is shown in Figs. 6 and 7, in which the auxiliary float chamber is dispensed with, and its functions are performed by the indicating-means secured to the dash or cowl of the automobile. 115

As here shown, the indicating-device is secured to the cowl 22 and inserted at a suitable point in the auxiliary fuel pipe 17 and is a modification of the cowl indicating-device previously described. It comprises a 120 glass tube 48 suitably secured in two supporting members 49 which are provided with flanged and threaded ends 50, by means of which the indicating-device is secured to the cowl 22 and to the ends 51, 52, of the 125 pipe 17. The hollow central ducts of the members 49 permit a free flow of fuel through glass tube 48. A ball 32 of cork or other material adapted to float upon the liquid fuel, is disposed within said glass 130

tube 48, and is free to move longitudinally therein, but is prevented from passing into pipe 17 because of the smaller diameter of the duct in member 49.

5 A valve seat 53 is provided in the lower part of glass tube 48 and is adapted to be closed by ball 32 when the main supply of fuel is exhausted, and valve seat 53 is provided with a by-pass 54 for a purpose to be 70
10 hereinafter explained. A check valve 55 is interposed in the auxiliary pipe 17 between the fuel tank 16 and the dash-indicating device to prevent a flow of fuel from the pipe 17 to the main fuel tank 16 when there is 75
15 atmospheric pressure in the vacuum tank.

That part of pipe 17 leading from the lower part of the indicating-device to the vacuum tank 10 is provided with a loop 31, which, in conjunction with check valve 55, 80
20 serves to normally maintain fuel in pipe 17, and the main fuel pipe 14, as here shown, is connected to pipe 17 at the top of this loop, for the purpose of providing substantially equal heads of fuel in both pipes.

25 With supply tank 16 full of fuel, the suction of the engine acting through suction pipe 13 creates a vacuum in vacuum tank 10, and induces a flow of fuel through the main pipe 14 into said tank. The vacuum in said 90
30 tank maintains ball 32 against its seat 53 in auxiliary pipe 17 and would normally prevent a flow of fuel in auxiliary pipe 17, but valve seat 53 is provided with a small by-pass 54 through which air can slowly pass, 95
35 and consequently, very soon after the engine has been set in motion, the suction of the engine raises fuel in pipe 17 and floats ball 32 from its seat. There is now an unobstructed passage for fuel flow through pipe
40 17, and consequently ball 32 is carried out of sight into upper member 49 and fuel flows through both the main pipe 14 and the auxiliary pipe 17 into vacuum tank 10, and this flow in both pipes continues until 100
45 the level of the fuel in the main supply tank 16 is at a point below the opening of auxiliary pipe 17. When this point is reached, air is drawn in said pipe, and the fuel contained therein is exhausted and consequently ball 32 falls into view in glass 105
50 tube 48, thereby indicating the exhaustion of the main fuel supply, and seats itself in valve 53, thus partially closing auxiliary pipe 17 from the vacuum tank 10, and permitting said tank to continue to draw fuel 110
55 from the reserve supply through the main pipe 14.

The by-pass 54 in valve 53, while admitting sufficient air to flow therethrough to 115
60 permit a normal flow of fuel through both supply pipes without undue delay, does not admit sufficient air, when the main fuel supply is exhausted, to interfere with the flow of fuel through main pipe 14 into vacuum tank 10.

A modification of the dash-indicator illustrated by Fig. 7 is shown in Fig. 8, in which the buoyant ball 32, coöperating with a valve seat 57 in the upper member 49, is designed to replace the separate check valve 55.

The operation of the check valve formed by ball 32 and valve seat 57 is exactly similar to the operation of check valve 55, the weight of the fuel in pipe 17 tending to maintain ball 32 on its seat 57, and thus to 70
75 prevent the emptying of said pipe when there is no vacuum in the vacuum tank 10, and to permit a flow of fuel through said pipe and dash-indicator when there is a vacuum in said tank 10. The other functions of the ball 32 are performed in this 80
85 modification as in the above-designed systems.

In order that the ball may not be carried down the glass tube 48, because of the normal flow of fuel down said tube, the impact pressure of the flowing fuel upon said ball must be less than the buoyancy of said ball in the fuel.

In the system shown in Fig. 6, the valve 90 or float 32 that is operated by the exhaustion of the main fuel supply to close the auxiliary fuel pipe 17 is disposed in the dash-indicator. Its disposition, to successfully 95
95 perform its functions as a float valve, is not limited to its position in the dash-indicating device, and, in Fig. 9, the float valve is shown disposed at the opening of the auxiliary fuel pipe 17 with the fuel tank 16.

The auxiliary fuel pipe 17, in this modification, is provided with an upturned end 58 to which is secured a casing 59 provided with the valve seat 60 and the ball valve 62 of cork or other buoyant material. As before, the valve seat 60 is provided with a by-pass 61 which is adapted to admit air slowly into pipe 17, when the fuel level in the supply tank is below the opening in said pipe, to clear said pipe of air and so permit the operation of the dash-indicating 110
115 device.

The dash-indicating device, in this modification, is essentially the same as before, a second cork ball replacing the ball 32 and serving merely to indicate the presence or 115
120 absence of fuel in the auxiliary pipe, as before.

The operation of this modification of the system is similar to the operation of the system shown in Fig. 6, the vacuum in the 120
125 vacuum tank normally causing a simultaneous flow of fuel in the main and auxiliary fuel pipes, and consequently maintaining the ball in the dash-indicating device out of view, and the lowering of the fuel level in the main supply tank 16 below a predetermined height operating to close the valve 32 at the end of the pipe 17, but permitting air to enter said pipe through slot 54 to cause the subsequent emptying of said pipe and 130

the consequent lowering of the float ball into view in the dash-indicator, while still permitting fuel to flow through the main fuel pipe into the vacuum tank.

5 I claim:—

1. In a fuel supply system a source of fuel, a place of fuel delivery, two pipes extended between said source and place of delivery and arranged for the normal simultaneous flow of fuel therethrough and means for automatically indicating the cessation of fuel flow in one of said pipes. 65
- 10 2. In a fuel supply system a source of fuel, a place of fuel delivery, two pipes extended between said source and place of delivery and arranged for the normal simultaneous flow of fuel therethrough and means connected with one of said pipes for automatically indicating the cessation of fuel flow in one of said pipes. 70
- 15 3. In a fuel supply system, a main supply of fuel, a reserve supply of fuel, a place of fuel delivery, a plurality of fuel pipes extending between said main and reserve fuel supplies to said place of delivery, and arranged for the normal simultaneous flow of fuel therethrough, and means operable upon exhaustion of the main fuel supply to automatically operate an alarm. 75
- 20 4. In a fuel supply system, a main supply of fuel, a reserve supply of fuel, a place of fuel delivery, a plurality of fuel pipes extending between said main and reserve fuel supplies to said place of delivery, and arranged for the normal simultaneous flow of fuel therethrough, and means operable upon exhaustion of the main fuel supply to operate an alarm and simultaneously operatively disconnect the fuel pipe extending 80
- 25 from the main fuel supply to the place of delivery. 90
- 30 5. In a fuel supply system, a source of fuel, a place of fuel delivery, a plurality of pipes extending between said fuel source and said place of delivery and arranged for the normal simultaneous flow of fuel therethrough, and means automatically operable upon cessation of fuel flow in one of said pipes to operatively disconnect said pipe 95
- 35 from the system. 100
- 40 6. In a fuel system, a variable supply of fuel, a place of fuel delivery, a plurality of fuel pipes connecting said supply of fuel with said place of fuel delivery and arranged for the normal simultaneous flow of fuel therethrough under a normal condition of fuel supply, and means automatically operated by an abnormal condition of fuel supply to control the flow of fuel 105
- 45 through certain of said fuel pipes. 110
- 50 7. In a fuel supply system, a variable supply of fuel, a place of fuel delivery, a plurality of fuel pipes connecting said supply of fuel with said place of fuel delivery, means for causing a simultaneous flow of fuel through all of said pipes under a normal condition of fuel supply, and means automatically operated by an abnormal condition of fuel supply to control the flow of fuel through certain of said fuel pipes, and to cause the actuation of an alarm. 120
- 55 8. In a fuel supply system, a variable supply of fuel, a place of fuel delivery, a plurality of pipes connecting said supply of fuel with said place of fuel delivery and arranged for the simultaneous flow of fuel therethrough under certain conditions of fuel supply, and means automatically operated by certain other conditions of fuel supply to control the flow of fuel through certain of said pipes. 80
- 60 9. In a fuel supply system, a variable supply of fuel, a place of fuel delivery, a plurality of pipes connecting said supply of fuel with said place of fuel delivery and arranged for the simultaneous flow of fuel therethrough under certain conditions of fuel supply, and means automatically operated by certain other conditions of fuel supply to control the flow of fuel through certain of said pipes to operate an alarm. 90
- 65 10. In a fuel supply system, a variable supply of fuel, a place of delivery, a plurality of pipes extended between said fuel supply and place of delivery and arranged for the normal simultaneous flow of fuel therethrough, and means for indicating the condition of said fuel supply, said means including a check valve arranged in one of said pipes, a seat therefor, said check valve arranged to be floated from its seat under a certain condition of fuel supply, and to be seated upon a certain other condition of fuel supply, and means for observing the position of said valve. 100
- 70 11. In a fuel supply system, a variable supply of fuel, a place of delivery, a plurality of pipes extended between said fuel supply and place of delivery and arranged for the normal simultaneous flow of fuel therethrough, and means for indicating the condition of said fuel supply, said means including a check valve arranged in one of said pipes, a seat therefor, said check valve arranged to be floated from its seat under a certain condition of fuel supply, means for observing the position of said valve and means providing a leakage path around said check valve in its seated condition. 115
- 75 12. In testimony whereof, I have signed my name to this specification, in the presence of two subscribing witnesses. 120
